By his Atty
Philip T. Dodge,

UNITED STATES PATENT OFFICE.

JOHN HENRY NEAVE, OF MACCLESFIELD, COUNTY OF CHESTER, ENGLAND.

METHOD OF AND APPARATUS FOR FINISHING FELT.

SPECIFICATION forming part of Letters Patent No. 271,351, dated January 30, 1883.

Application filed February 13, 1882. (Model.) Patented in England May 11, 1881, No. 2,051.

To all whom it may concern:

Be it known that I, JOHN HENRY NEAVE, of Macclesfield, in the county of Chester, in the Kingdom of England, have invented certain new and useful Improvements in Method of and Apparatus for Finishing Felt, (for which I have received Letters Patent in England, No. 2,051, dated May 11, 1881,) of which the following is a specification.

10 This invention consists in a new method of and apparatus for finishing felt goods.

Hitherto felt has been finished by subjecting its surface to a grinding operation, commonly known as "pouncing," of such character as to cut away the extraneous ends of the fibers and produce a smooth, uniform surface, after which the surface was subjected to a long-continued ironing operation to produce the required gloss or polish thereon. My new process differs from the old in the highly-important particular that I do not grind or cut away the protruding ends of the fiber, but, instead of so doing, drag or pull the ends of the fibers outward beyond the body, so that they will lie

25 upon the surface and form a nap. By my process, indeed, one can take a felt hat which has no nap and draw a nap out till it resembles a beaver or silk hat with a copious long dense nap of bright, polished hairs. The process is 30 most successfully carried out by bringing the hats or felt goods into contact with a rapidly-revolving abrasive surface; or the same result may be obtained by bringing the prepared surface into contact with the felt, revolving at sufficient velocity, or by means of emery and

35 glass, rouge, or other abrasive powder inserted between the felt and covering-surface while said felt or covering-surface are revolving. This may be accomplished by holding the felt goods against a stone, emery-wheel, or cylinder covered with sand, glass, or emery, or other suitable roughened or cutting surface, prepared in such a manner as not to possess too great a cutting-power, but revolving with sufficient velocity—say three thousand or more revolutions a minute—or by means of emery, sand, glass, rouge, or other suitable powder inserted between the hat and covering-surface, while the said hat or covering-surface is re-

45 volving, to produce a smooth feeling and polished surface on the hat operated upon, at the

same time, however, possessing sufficient roughness to not merely polish the hairs, but to catch hold of loops and drag them out into a nap varying in length with the roughness of the surface used. The abrasive surfaces employed are to be of a rougher or coarser character than those used in the ordinary grinding or pouncing operation; and particular attention is to be paid to maintaining them in such condition that they will take a firm hold upon the fibers and, without severing or cutting them loose, draw their ends outward beyond the body of the felt. In the manipulation of the felt particular care is to be taken to so graduate the pressure as to avoid a grinding or cutting action such as would remove the fiber. Having this precaution and the end sought in mind, the operator will quickly learn to loosen and draw out the ends of the fibers and leave them on the surface in the shape of a thick polished nap. The product presents to the eye a strong resemblance to fur, and is without the smooth, hard surface presented by felt finished in the usual manner. For this purpose machines of various designs may be used. A simple form for such machine is shown in the annexed drawings, Figure 1.

A is a shaft, supported by pedestals or framework, marked B. At one end of the shaft is fixed 80 a drum or cylinder, C, covered with a prepared surface of graded powdered glass, emery, sand, or other similar material. D D are fast and loose pulleys for driving the shaft A. When revolving with sufficient velocity the hat or other goods to be operated upon is placed upon the rest E and brought into contact with revolving cylinder C by the operator placing his foot upon the treadle H, by means of which the amount of pressure on the hat may be regulated. The hat or other piece of felt or felt goods will be drawn slowly over the rest E by the friction of the cylinder C, and will be guided and controlled by the hand of the operator, who will be able to pass the felt article 90 round until the whole is operated upon.

The size and shape of the drum and rest may be varied in any way for greater facility in getting the shape of the hat or other goods operated upon. This may be especially desirable in 100 finishing ladies' hats and other fancy shapes. The tip of the hat may, however, be more readily

operated upon by placing the hat over the rest J in such a way as to bring the inside of the tip against the rest, and by means of the treadle and connecting-rods M bringing the top or 5 crown of the hat against the disk K, which is covered with a similar surface to the drum or cylinder C. The hat will be similarly drawn round by the friction of the disk K, and will 10 be guided and controlled by the hand of the operator.

The rests E and J are preferably padded with an air-tight india-rubber padding filled with air, as in sectional views 2 and 3. The air inside the pad quickly adjusts itself to any 15 inequality in the felt, and will cause an even surface always to be presented to the cylinder or disk, and insure an equal bright polish upon all parts of the surface of the felt. This pad is covered. The rests E and J are by preference 20 covered with a pad. As a matter of convenience, the drum or cylinder C is placed outside of the pedestals or frame-work which supports the shaft A; but it is obvious that the same result might be obtained by placing it 25 between these pedestals.

The pressure of the hats or other goods against the drum and disk may be regulated by a spring or tension, instead of the treadle arrangement, when found more convenient, and 30 many other modifications of the machine may be made.

If it be desired to finish the goods while they remain upon the block, this may be accomplished by bringing them while upon the block 35 into contact with the drum or cylinder covered with the prepared surface.

Various known methods may be adopted for keeping the oval block against the drum with an equal pressure; and the drum may be made 40 concave or convex, or any other shape to correspond with the shape of the block; and the disk K may also be made to correspond with the shape of the block, which may be placed upon the rod P in place of the rest J, and the 45 hat while upon the block thus be brought into contact with the disk and the tip operated upon; or the result may be accomplished by means of a band or strap covered with the prepared 50 cutting or polishing surface being passed at sufficient velocity over the hats while upon the block.

By attention to the condition of the polishing or cutting surface different results may be

obtained, as desired, and according to the degree of fineness of the stone, emery, glass, or other material used for the roughened surface, a longer or shorter nap or pile may be obtained and a greater or less degree of luster or polish obtained. By this process are capable of being produced an unusual gloss and softness and fineness of touch. This process of finishing is equally applicable to felt cloths; but instead of a drum or cylinder of narrow dimensions it will be desirable to have a roller 55 covered with the prepared surface of the same width as the cloth to be operated upon. This roller being driven at a rapid speed and the cloth pressed against it and allowed to travel at a uniform but much slower speed, the piece will be operated upon through its own length. 60 Instead of employing a treadle, the pressure of the cloth against the polishing-roller may be more easily regulated by means of a rest or roller fixed rigid in proximity to the polishing-roller, or pressed against it by means of levers 75 and weights, or by springs or tensions, or in any other convenient way.

If an embossed or deeply-cut roller or block be used for the cloth or article to pass over or be placed upon when pressed against the polishing or cutting roller, drum, or surface, patterns of various designs may be produced.

I claim as my invention—

1. As a new article of manufacture, the herein-described felt, consisting of a close web or 85 body having on its surface a nap consisting of polished ends of hair or fiber extending out of and beyond the body portion.

2. The improved method of finishing felt to produce an artificial nap thereon, consisting in 90 subjecting the felt surface to the action of an abrasive surface and graduating the speed and pressure, as described, in connection with suitable backing, whereby the ends of the fibers are drawn outward beyond the body of the 95 felt, leaving them upon and attached to the surface in a polished condition.

3. The method of finishing felt, consisting in drawing the ends of the fibers outward and beyond the body, leaving them attached thereto at the inner ends, substantially in the manner herein set forth.

JOHN HENRY NEAVE.
